UNITED STATES PATENT OFFICE.

CLAIR A. NESBIT, OF FAIRBURN, SOUTH DAKOTA.

CONCRETE TIE.

Application filed February 6, 1923. Serial No. 617,237.

To all whom it may concern:

Be it known that I, CLAIR A. NESBIT, a citizen of the United States, residing at Fairburn, in the county of Custer and State of South Dakota, have invented certain new and useful Improvements in Concrete Ties, of which the following is a specification.

This invention relates more especially to a concrete tie and it has for its primary object to provide a tie which will be economical in construction and may be readily manufactured at a cost favorable in comparison with the wooden tie.

The invention further resides in a concrete tie having central as well as lengthwise reinforcement.

Further, the invention resides in the features of construction and the arrangements and combinations of parts hereinafter described, reference being made to the accompanying drawing wherein,

Figure 1, is a perspective view of a concrete tie constructed in accordance with the present invention;

Figure 2, is a fragmentary, longitudinal section therethrough; and

Figure 3 is a transverse central section of the tie.

Referring more in detail to the accompanying drawing, the concrete body 1 is cored out at each end to provide a tapered opening 2 which extends inwardly to a point adjacent the center so as to leave a solid central portion 3 of considerable size. The tie is reinforced lengthwise by upper and lower series of rods 4 which extend substantially parallel to the adjacent tapering wall of the opening 2. Consequently, the longitudinal reinforcing rods 4 extend toward the longitudinal axis from each end and each rod is therefore bowed, in effect, with the central portions of the two series being closer together than their extremities. The central portion 3 of the tie is also reinforced by a plurality of rows of vertical rods or reinforcing members 5. This construction and arrangement of the reinforcing rods provides a tie that is effectively reinforced with particular attention being given the central portion of the tie, which portion has been found weak in concrete ties of former constructions.

Transversely across the top of the tie are the rail seats 6 slightly depressed to receive the bases of the rails. Each rail base is held

seated or in position by a pair of anchor plates 7 disposed on opposite sides of the rail and overlapping the base, said plates being secured in position by a pair of bolts or a U-bolt 8 which is passed upwardly through a pair of vertical openings in the tie. These openings lead from the tapered recesses 2 to the top surface of the tie and the tapered recesses are of sufficient size to permit the introduction of the U-bolts into the vertical openings. The free extremities of the U-bolts pass through the anchor plates and are threaded to receive the nuts 9. Said anchor plates are provided with lugs 10 on their underfaces to fit in corresponding recesses 11 in the top surface of the tie to prevent turning of the plates from their operative position. Also a wooden block or cushion 12 is interposed between the base of each U-bolt and the upper wall of the respective tapered opening 2 to provide for yieldable or cushioning clamping of the rail as in the case of the wooden tie, the block 12 being cut on the bias to conform to said upper wall.

What is claimed is:

1. A concrete tie comprising a cement body having a tapered opening extending from each end beneath the rail-supporting portions and terminating adjacent the center so as to leave a central solid portion.

2. A concrete tie comprising a cement body having a tapered opening extending from each end beneath the rail-supporting portions and terminating adjacent the center so as to leave a central solid portion, and a reinforcement for the central portion.

3. A concrete tie comprising a cement body having a tapered opening extending from each end beneath the rail-supporting portions and terminating adjacent the center so as to leave a central solid portion, vertical reinforcing rods in the central portion, and longitudinal reinforcing rods extending the length of the body.

4. A tie comprising a concrete body having end openings extending inwardly and terminating short of the center to leave a central solid portion, and means leading from each opening, upwardly for anchoring a rail to the tie.

5. A tie comprising a concrete body having end openings extending inwardly and terminating short of the center to leave a central solid portion, lengthwise reinforcement for the body, transverse reinforcement

for the central portion, and means leading from each opening upwardly for anchoring a rail to the tie.

6. A tie comprising a concrete body having end openings extending inwardly and terminating short of the center to leave a central solid portion, U-bolts insertible

through the openings upwardly through the body, means cooperating with the bolts for attaching rails to the tie, and cushion means between the bases of the U-bolts and the upper walls of the openings of said tie. ¹⁰

In testimony whereof I affix my signature.

CLAIR A. NESBIT.
